(57) **CLAIM**

The ornamental design for exterior shielding of a combine harvester, as shown and described.

DESCRIPTION

FIG. 1 is a front, left perspective view of exterior shielding of a combine harvester showing our new design.

FIG. 2 is a rear, left perspective view of the exterior shielding of FIG. 1.

FIG. 3 is a front, right perspective view of the exterior shielding of FIG. 1.

FIG. 4 is a rear, right perspective view of the exterior shielding of FIG. 1.

FIG. 5 is a left side view of the exterior shielding of FIG. 1.

FIG. 6 is a right side view of the exterior shielding of FIG. 1.

FIG. 7 is a rear view of the exterior shielding of FIG. 1.

FIG. 8 is a front view of the exterior shielding of FIG. 1.

FIG. 9 is a top view of the exterior shielding of FIG. 1; and, FIG. 10 is a bottom view of the exterior shielding of FIG. 1. The dashed lines shown in the figures are for illustration only and do not form part of the claimed design.

1 Claim, 9 Drawing Sheets
